US0D1018020S

(12) United States Design Patent (10) Patent No.: US D1,018,020 S
(45) Date of Patent:  Mar. 19, 2024

(54) COSMETIC BAG

(71) Applicant: Kunyang Zhan, Jiangxi (CN)

(72) Inventor: Kunyang Zhan, Jiangxi (CN)

() Term: 15 Years

(21) Appl. No.: 29/885,000

(22) Filed: Feb. 17, 2023

(51) LOC (14) Cl. 03-01

(52) U.S. Cl.

USPC D3/205

(58) Field of Classification Search

USPC D3/205, 212, 226, 229, 232, 233,

D3/243-246, 273, 276-277, 283,

D3/285-287, 289-291, 301, 303, 901
